UNITED STATES PATENT OFFICE.

ISAAC A. ROMMER, OF BROOKLYN, NEW YORK, ASSIGNOR, BY MESNE ASSIGNMENTS,
TO VOICES INCORPORATED, A CORPORATION OF DELAWARE.

TALKING MECHANISM FOR TOYS.

Application filed April 25, 1922. Serial No. 556,389.

To all whom it may concern:

Be it known that I, ISAAC A. ROMMER, a citizen of the United States, and a resident of the city of New York, borough of Brooklyn, in the county of Kings and State of New York, have invented new and useful Improvements in Talking Mechanisms for Toys, of which the following is a full, clear, and exact description.

10 This invention relates to sound producing devices and was primarily designed as a voice for dolls whereby they may be caused to utter sounds like ma-ma, pa-pa, etc.

15 The general object of the invention is the provision of a durable and simple sound producing mechanism that is compact in design and cheap to construct.

20 A more specific object of the invention is the provision of a sound producing mechanism operated by slidable weight means which are provided with guides external to the bellows.

25 Another object is the construction of a sound producing mechanism protected by a casing spaced a distance from the guiding means so that an indent in the casing does not interfere with the operation of the slideable weight means.

30 A further object is the provision of two chambers located externally to the bellows, said chambers being provided with a sound producing reed and having associated therewith means for controlling the sound.

35 These objects are accomplished by mounting in a casing a weight-controlled bellows, providing, in conjunction with the weight operating means, guides spaced from the casing, mounting, on the bellows, chambers for enclosing the sound producing means, and associating with the chambers means 40 for controlling the sounds.

These and other objects of the invention will be more clearly understood from the following detailed description and accompanying drawings.

45 Figure 1 is a section along the line 1—1, Figure 2, showing a top plan view of the mechanism;

Figure 2 is a section along the line 2—2, Figure 1;

50 Figure 3 is the same section as shown in Figure 2 but inverted, showing how the weight operating means extends the bellows;

Figure 4 is a section along the line 4—4, Figure 2;

Figure 5 is a side elevation of the device 55 with a portion of the casing broken away.

Referring to the above-mentioned drawings, a bellows 10 is shown mounted in the tubular cylindrical casing 11, with its lower end attached to the bottom of the casing by 60 means of a plate 12. The casing 11 has an opening 31 provided in its upper end. Secured to the top member of the bellows is a horseshoe-shaped weight 13 which serves to extend and collapse the bellows as the casing is first inverted and then returned to its upright position. Mounted on the said top member or upper end of the bellows and in the weight, are two cup shaped members forming with the top member of the bellows, 70 two chambers 14 and 15. The smaller chamber 15 is inverted over an opening 16 in the top of the bellows. Sound chamber 14 is provided with an opening 17 in its upper end so as to allow communication with the 75 atmosphere. As shown in the drawings the top member of the bellows which forms the lower side of the sound chamber 14 serves to hold the weight 13 connected with the bellows, said top member of the bellows frictionally clamping and holding the top member of the top periphery of the bellows member in a peripheral groove in the weight. A valve 19 made of some elastic material is provided for closing the opening 17 in the 85 chamber 14. This valve is operated by means of a weight 18 attached thereto. A reed pipe 21 carrying a reed that is operated by the air flowing in one direction only through the pipe establishes communication between the chambers 14 and 15, the sound issuing into the chamber 14 from which the sound issues through the sound opening 17.

Two vertical guides or posts 20 and 22 95 provided for guiding the movements of the weight 13 are mounted in the casing 11. These guiding posts act to support the weight away from the sides of the casing and the weight is freely slideable along the 100 posts. Projections 23 and 24 which extend beyond the weight 13 are provided with openings which are in alignment for loosely fitting over the guide 20 so that, as the weight moves, the projections slide along the guide. Directly opposite the projections 23 and 24 is another projection 25 which has a groove 26 cut therein. This groove is 105

adapted to engage the guide 22 so as to prevent the rotation of the weight about the guide 20. The two projections 23 and 24, slidably mounted on the guide 20, are spaced 5 apart so as to prevent the possibility of them binding so that the weight will not move. The guides are spaced from the casing 11 so that if an indent is made in the casing through rough handling it is not likely to 10 be sufficiently deep to prevent the operation of the weight.

The valve 19 is pivoted on the weighty member 13 and is operated through a crank 27 fixed with respect to the valve which is 15 rotatably mounted on the weight 13 by bending over it raised strips 32 of the metal from which the weight is constructed. This valve crank 27 is provided with an integral arm 28 which is fixedly connected to the weight 20 18 mounted on and forming part of the valve 19. An actuating rod 30 provided with a number of projections is mounted in the casing for operating the crank 27. This operation is accomplished as the weight 25 slides along the guides by the actuating rod 30 engaging the arm 29 of the crank 27. Thus the valve 19 will periodically close the opening 17.

In the operation of the device consider it 30 as shown in Figure 2. The bellows is collapsed and the opening 17 is closed by the valve 19. On inverting the casing the bellows is extended by the weight 13 and the valve 19 is removed from the opening 17. 35 As the weight 13 moves down the guides to the position shown in Figure 3 air passes in through the opening 17, reed pipe 21 and opening 16 into the bellows 10. On turning the casing 11 to an upright position again, 40 the air is forced through the opening 16, reed pipe 21 and opening 17. The reed in the reed pipe 21 is vibrated, producing a sound and this sound is controlled by the valve 19 as it periodically opens and closes 45 the opening 17 to cause the device to utter sounds simulating "ma-ma" or the like.

I would state in conclusion that while the illustrated example constitutes a practical embodiment of my invention, I do not limit 50 myself strictly to the exact details herein illustrated since manifestly the same can be considerably varied without departing from the spirit of the invention as defined in the appended claims.

55 Claims:

1. A sound producing device comprising a casing, a bellows mounted in the casing, weight means mounted on the bellows for operating it, guides fixed in the casing external to the bellows and co-operating with the weight means to guide its movement, and means associated with the bellows for creating and controlling the sound.

2. A sound producing device having in 60 combination a casing, a sound chamber hav-

ing air inlet and air outlet openings therein, said chamber being weighted and sliding by gravity back and forth in the casing, means whereby movement of said chamber in the casing will cause air to be forced through the chamber as it slides in the casing, a sound reed mounted in the inlet opening of the sound chamber, and means for controlling the sound associated with the other opening.

3. A sound producing device comprising a casing, a bellows mounted in the casing, weight means attached to the bellows for operating the same, guiding means mounted in the casing external to the bellows, means provided in conjunction with the weight means for connecting it with the guide means, and means associated with the bellows for creating and controlling sound.

4. A sound producing device of the class described, comprising a casing, a bellows mounted in the casing, weight means for operating said bellows, guides mounted in the casing external to the bellows, and means interposed between the weight means and the guides for connecting the former to the latter, and means associated with the bellows for creating and controlling sound.

5. As a new article of manufacture, a sound producing device of the class described, comprising a casing, a bellows mounted in the casing, weight means attached to the bellows for operating the bellows, guides mounted in the casing, means for establishing a slidable connection between the weight means and the guides, means associated with the bellows for producing sound, and means associated with the sound producing means and operated by the movement of the weight for controlling the sound.

6. A sound producing device comprising a casing, a bellows mounted in the casing, a weight mounted on the bellows for operating it, two guides mounted in the casing, two spaced projections formed on one side of the weight and slidably connected to one of said guides, a grooved projection formed on the opposite side of the weight from said first mentioned projections and slidably engaging the other guide, and means associated with the bellows for producing and controlling sound.

7. A sound producing device comprising a casing, an air chamber having air inlet and air outlet openings formed therein slidably mounted in the casing, means associated with the air chamber for forcing air through it as it slides in the casing, an air operated sound producing member mounted in one of said openings, means for controlling the sound associated with the other opening, and means for operating said sound controlling means.

8. A sound producing device comprising

1. A tubular casing, a weighty member slidable back and forth in the casing by gravity, a reed pipe carried with the weighty member and operated by air forced therethrough by movement of the weighty member, a pivoted valve carried by the weighty member for controlling the sound from the reed pipe and a control member fixed with respect to the casing for actuating said valve as the weighty member slides in the casing. 90
2. A sound producing device comprising a tubular casing, a weighty member slidable back and forth in the casing by gravity, a reed pipe carried with the weighty member and operated by air forced therethrough by movement of the weighty member in the casing, said weighty member having a sound chamber carried therewith and into which the sound from the reed pipe issues, said sound chamber having an opening through which the sound may issue, a valve pivoted with respect to the weighty member and adapted to open and close said opening, and a control member fixed with respect to the casing and having a plurality of projections adapted to engage a part fixed with respect to the valve to operate the valve. 105
3. A sound producing device comprising a tubular casing, a weighty member slidable back and forth in the casing by gravity, a reed pipe carried with the weighty member and operated by air forced therethrough by movement of the weighty member, a valve carried by the weighty member having a sound chamber into which the sound from the reed pipe issues, a valve carried by the weighty member and adapted to open and close an opening in the sound chamber to control the sound from the reed pipe, and means automatically controlling said valve. 115
4. A sound producing device comprising a tubular casing, a weighty member slidable back and forth in the casing by gravity, a reed pipe carried with the weighty member and operated by air forced therethrough by movement of the weighty member, a valve carried by the weighty member and adapted to control the sound from the reed pipe, and means automatically controlling said valve, said means comprising a control member fixed with respect to the casing and acting directly on an arm attached to the valve. 125
5. A sound producing device comprising a tubular casing, a weighty member slidable back and forth in the casing by gravity, a reed pipe carried with the weighty member and operated by air forced therethrough by movement of the weighty member, a pivoted valve carried by the weighty member for controlling the sound from the reed pipe, said valve having an arm, and control means fixed with respect to the casing and engaging said arm to operate the valve as the weighty member slides along a casing. 135
6. A sound producing device comprising a casing, a weighty member slidable back and forth in the casing by gravity, a reed pipe carried with the weighty member and operated by air forced therethrough by movement of the weighty member, a valve for controlling the sound from the reed pipe and means automatically causing the operation of said valve as the weighty member moves in the casing. 145
7. A sound producing device comprising a casing, a weighty member slidable back and forth in the casing by gravity, a sound chamber carried by and with the weighty member and into which the sound from the reed pipe issues, said chamber having an opening from which the sound may escape to the atmosphere, a valve adapted to open and close said opening, said valve being movable relatively to the weighty member and the casing, and means for automatically controlling said valve as the weighty member moves in the casing. 155
8. A sound producing device comprising a casing, a weighty member slidable back and forth in the casing by gravity, a reed pipe carried with the weighty member and operated by air forced therethrough by movement of the weighty member in the casing, said weighty member having a sound chamber carried therewith and into which the sound from the reed pipe issues, said sound chamber having an opening through which the sound may issue, a valve pivoted with respect to the weighty member and adapted to open and close said opening, and a control member fixed with respect to the casing and having a plurality of projections adapted to engage a part fixed with respect to the valve to operate the valve. 165
9. A sound producing device comprising a tubular casing, a flexible bellows member therein, one end of which is secured with respect to the casing, a weighty member connected to the other end of the bellows member and adapted to slide back and forth in the casing by gravity, a reed pipe carried by the weighty member, a sound chamber also carried with the weighty member and into which the sound from the reed pipe issues, said chamber having an opening through which the sound may issue, a valve pivoted on the weighty member, and a control member fixed with respect to the casing and adapted to operate the valve as the weighty member moves in the casing. 175
10. A sound producing device comprising a tubular casing closed at one end, a weighty member slidable back and forth in the casing by gravity, a reed pipe connected to be operated by air forced therethrough due to the movement of said weighty member, a valve member for controlling the sound from the reed pipe, said valve being movable relatively to the weighty member and casing, and means automatically controlling said valve responsive to the movement of said weighty member in the casing. 185
11. A sound producing device comprising a tubular casing closed at one end, a weighty member slidable back and forth in the casing by gravity, a reed pipe connected to be operated by air forced therethrough due to the movement of said weighty member, a valve member and a control member, one carried by the weighty member and the other carried by the casing, the valve member controlling the sound from the reed pipe, and the control member being fixed to the part which carries the same and acting directly on the valve member. 195
12. A sound producing device having in

combination a tubular casing, a member adapted to slide back and forth in the casing by gravity, a sound reed carried by said member and adapted to be operated by air moved thereby by movement of said gravity operated member in the casing, a sound chamber carried by said member and into which the sounds from the reed issue, said sound chamber having an opening through which the sounds may issue therefrom, valve means for controlling said opening as the said member moves by gravity in the casing, and a rod in the casing, said rod extending in a direction substantially parallel to the direction of movement of said gravity operated member and having means for engaging said valve means to affect the action of said valve.

19. A sound producing device having in combination, a tubular casing, a tubular bellows within said casing, means closing one end of said casing and bellows, a weighty member secured to the other end of said

tubular bellows and adapted to slide by gravity back and forth in the casing to compress and distend said bellows, a sound reed carried by said member and operated by air forced out of said bellows by movement of said member by gravity, a sound chamber carried by said member and into which the sounds from the reed issue, said sound chamber having an opening through which the sounds may issue therefrom, a valve for controlling said opening as the said member moves by gravity in the casing, and a rod in the casing said rod extending in a direction substantially parallel to the direction of movement of said gravity operated member and having means for engaging a part associated with said valve to cause the valve to be open a plurality of times during a single movement of the gravity operated member whereby a plurality of sounds will issue from the device during one movement of the gravity operated member.

ISAAC A. ROMMER.
